CURRENCY CLIP

**Hubert Pickering Harmon, Jr., Mexico City,
Mexico****Application November 4, 1947, Serial No. 142,289****Term of patent 7 years****(Cl. D74—2)****To all whom it may concern:**

Be it known that I, Hubert Pickering Harmon, Jr., a citizen of the United States of America, residing at Mexico City, Mexico, have invented a new, original, and ornamental Design for a Currency Clip, of which the following is a specification, reference being had to the accompanying drawing, forming a part thereof, wherein the figure on the drawing is a perspective view of a currency clip showing my new design, the back of the same being substantially plain.

I claim:

The ornamental design for a currency clip, as shown and described.

HUBERT PICKERING HARMON, JR.
